UNITED STATES PATENT OFFICE.

JOHN NIELSEN, OF CHICAGO, ILLINOIS.

REVERSING-VALVE FOR STEAM-ENGINES.

SPECIFICATION forming part of Letters Patent No. 758,772, dated May 3, 1904.

Application filed March 27, 1902. Serial No. 100,288. (No model.)

To all whom it may concern:

Be it known that I, JOHN NIELSEN, a citizen of the United States, residing at Chicago, in the county of Cook and State of Illinois, have 5 invented a new and useful Reversing-Valve for Steam-Engines, of which the following is a specification.

This invention relates generally to steam-engines, and more particularly to an improved 10 reversing mechanism particularly adapted for use in connection with locomotives, the object being to provide a construction which shall be cheaper and simpler than those now in general use, inasmuch as it avoids the use of the 15 link mechanism and also the complicated valve reversing mechanisms.

Another object of the invention is to provide for a central location of the cylinder and steam-chests, whereby the piston-rods can be 20 connected at opposite ends with the driving-wheels, thereby throwing the entire weight of the locomotive upon the driving-wheels and quickly distributing the power to the wheels.

With these various objects in view the invention consists in the novel features of construction and combination, all of which will 25 be fully described hereinafter and pointed out in the claims.

In the drawings forming part of this specification, Figure 1 is a side elevation of a locomotive provided with cylinders and steam-chests constructed and arranged in accordance with my invention. Fig. 2 is a horizontal sectional view taken through the said cylinders and steam-chest. Fig. 3 is a section taken 30 on the line 3 3 of Fig. 2. Fig. 4 is a plan view, partly in section, illustrating the operation of the flap-valve. Fig. 5 is a diagrammatic plan view of the pipe connection between 35 the throttle-valve and the steam-chests, the latter being removed. Fig. 6 is a detail sectional view of a valve, showing means for regulating admission of steam to the pipes.

In carrying out my invention I employ a 40 central steam-chest A, and upon opposite sides thereof I arrange supplemental steam-chests B, and upon the outer side of each steam-chest B is arranged a cylinder C, and working in each cylinder is a piston D, the piston-rods E working 45 through the opposite ends of the cylinder-

heads. The central steam-chest A has two slide-valves A', which are substantially the same as the ordinary slide-valve now in common use, and each steam-chest B has a slide-valve B', which is similar in construction to the 55 slide-valves now in use. These slide-valves A' and B' are operated by the valve-stems A² and B², respectively, which are connected with eccentrics (not shown) in the proper manner, one set being arranged upon one side 60 of the center of the engine, the other upon the opposite side of the center. It is to be understood that the cylinders and steam-chests (shown in Fig. 2) extend entirely across the under side of the engine, (shown in Fig. 1,) 65 one of the piston-rods driving the wheels on one side of the engine and the other those upon its opposite side. A space or chamber F surrounds each steam-chest B, and flap-valves G are located at each end of each cylinder C, as 70 most clearly shown in Fig. 2.

In the lower central portion of each steam-chest is a steam-inlet, those in the side chests B being indicated at b and that leading to the central steam-chest at a.

A main steam-pipe (not shown) leads from the boiler and divides into three branches, leading, respectively, to the inlets a and b b.

In operation the steam is directed to either the central steam-chest through the inlet a or 80 to the side chests through the inlets b b. In Fig. 2 I have shown the steam as being directed to the side steam-chest, and the operation will then be exactly the same as though each side steam-chest had no connection whatever with the central steam-chest. The flap-valves G are pivoted to the wall of the chamber B adjacent the cylinder C and are adapted to close the passage F when steam is being fed to the cylinder C from the chamber B, the 85 pressure of the steam holding the valve closed. When, however, steam is used from the central chamber, it will pass through one of the passages F (which one is immaterial) and force one of the valves open, as shown 90 in Fig. 4. The pivotal rods G' of each flap-valve extend upward through the casing and carry oppositely-arranged links G², which links are pivotally connected at their outer ends by a rod G³. Through the medium of 100

these links and the rod the valves are moved in opposite directions, and the opening of one valve will therefore open the other valve, as shown in Fig. 4. When, therefore, steam 5 passes through the passage F on one side of the chamber B, it will open the valves G, controlling both passages, and will therefore enter the cylinder at one end and exhaust at the other. These valves once opened will remain open until steam is cut off from the chamber A and directed into chamber B. To regulate admission of steam to the steam-chests, I employ a throttle-valve H, arranged in a steam-pipe H', leading from the boiler. 15 This is a two-way valve and is adapted to open communication between the pipe H' and the pipe J or J', these pipes leading from the casing of the valve H at right angles to each other, so that when the valve is shifted to 20 bring the port H² between the pipes J and J' steam will be cut off from each. The pipe J leads to the central chest A, discharging steam into said chest through the inlet a, and the pipe J' divides into two branches J² and J³, 25 which discharge, respectively, into the chests B through the inlets b.

It will thus be seen that I employ a single central steam-chest by means of which I am enabled to distribute steam to the cylinders 30 at the opposite sides whenever it is desired before reversing the movement of the engine and that when an engine is being run from the central steam-chest its motion can be reversed by cutting off the steam from the central steam-chest and applying steam to the side steam-chest. It will also be noted that owing to the 35 construction of my invention I am enabled to locate the cylinders beneath the boiler and midway beneath the driving-wheels, connecting the said driving-wheels with the opposite ends of the piston-rods, thereby distributing the power evenly to the said drive-wheels, and, furthermore, by locating the cylinder centrally and between the drive-wheels the entire weight 40 of the locomotive can be supported upon the said drive-wheels.

It will be understood that I have shown the cylinders and steam-chests applied to a rail-

way-locomotive for illustration only, the locomotive being no part of my invention, which 50 can be applied to stationary and marine engines as well as to locomotives.

Having thus fully described my invention, what I claim as new, and desire to secure by Letters Patent, is—

55

1. In an engine the combination with cylinders, a piston working therein, of the steam-chests connected with the said cylinders, and a central steam-chest arranged between the first-mentioned steam-chests and operatively 60 connected with the cylinders for the purpose described.

2. A steam-engine comprising a central steam-chest, supplemental chest arranged upon opposite sides, and the cylinders arranged 65 upon the outer sides of the supplemental chest, each supplemental steam-chest having a chamber surrounding the same and valves arranged at each end of the cylinder for controlling the inlet and outlet of the steam from the central 70 steam-chest, substantially as specified.

3. The combination with a central steam-chest having ports at the opposite sides and slide-valves operating upon the said ports, the supplemental steam-chest communicating 75 with the main or central steam-chest and surrounded by a chamber having flap-valves at each end, slide-valves arranged in each supplemental steam-chest, the cylinders operatively connected with both the main and supplemental steam-chest, the pistons working there-in, and the piston-rods passing through the opposite ends of the cylinders for the purpose specified.

4. In an engine, the combination with a plurality of cylinders having pistons therein, of a central steam-chest between the cylinders, supplemental steam-chests independent of the central chest arranged adjacent the cylinders, and means for admitting steam to the cylinders from either the supplemental or the central steam-chest at the will of the engineer.
